UNITED STATES PATENT OFFICE.

GOTFRID CARLSON, OF CHICAGO, ILLINOIS.

ADJUSTABLE HOOD FOR COOKING-STOVES.

SPECIFICATION forming part of Letters Patent No. 369,161, dated August 30, 1887.

Application filed March 3, 1887. Serial No. 229,538. (No model.)

To all whom it may concern:

Be it known that I, GOTFRID CARLSON, a subject of the King of Sweden and Norway, and a resident of Chicago, in the county 5 of Cook and State of Illinois, have invented a certain new, useful, and Improved Adjustable Hood for Cooking-Stoves, of which the following is a description, reference being had to the accompanying drawings, forming a part 10 of this specification, in which—

Figure 1 is a side view of a cooking-stove to which my adjustable hood is applied. Fig. 2 shows plan, face, and sectional side views, respectively, of a clamp for engaging the adjusting-rod. Fig. 3 shows sectional, side, and 15 face views, respectively, of a portion of the adjusting-rod. Fig. 4 embraces plan and face views, respectively, of the bracket which sustains the hood against the stove-pipe; and Fig. 20 5 shows a side view in detail of a portion of the adjusting-rod and locking device, and also a plan view of the same partly in section.

Like letters of reference indicate like parts in the different figures.

25 The object of my invention is to provide a hood for cooking-stoves and ranges, which may be raised and lowered at will and adjusted to any desired height, all of which I accomplish substantially in the manner hereinafter more particularly described and claimed.

A in the drawings represents an ordinary cooking-stove having a pipe, B, connected therewith and arranged in the usual manner.

35 Attached thereto is a smaller horizontal pipe, C, having an elbow, D, attached to and depending therefrom. Rigidly secured to said elbow is a vertical section of pipe, E, to which are in turn loosely connected two or more telescoping pipe-sections, F G, to the bottom of the latter of which is secured a hood, H.

The pipes C E are maintained in place and prevented from sagging by means of a bracket, J, riveted thereto and to the pipe B. A cord, 45 K, attached to an eye, K', trained over a pulley, K'', secured to the bracket and having a weight, K'', attached to its opposite end, is preferably employed to balance the weight of the hood H. A casting having a face-plate, 50 H', and curved portion H'', (shown in detail in Fig. 4,) is rigidly attached to said hood, so

that the curved portion may bear loosely against the pipe B, thus serving to protect both the pipe and hood from injury. A series of eye brackets or guides, L, having curved plates or flanges L', are riveted through said flanges to the sections E, F, and G, respectively. Through the eyes in said brackets is passed an adjusting-rod, M, having a series of notches, m, formed in one side thereof. A 60 depending hook, L'', Figs. 1 and 2, is formed preferably, upon the uppermost bracket L and is designed to engage with said notches. A pin or screw, m', upon the lower end of the rod and above the lowermost bracket serves 65 to keep said rod in place. The lower end of the rod is bent outwardly, as at L'', and forms a handle for use in its adjustment. The lower bracket L is cut away at l, Fig. 5, upon which face the pin m' rests, the lateral movement of 70 the rod being limited thereby to a quarter of a revolution, as indicated in dotted lines in said Fig. 5. The resiliency of the rod serves to keep the notches m in engagement with the hook L''; but, in view of the direction of the 75 slant given to said notches, it is evident that the rod may be readily pushed upwardly, and with it the hood H, the sections E F G telescoping each other. Upon turning said handle in the direction represented by the arrow 80 shown in Fig. 5, the smooth side of the rod is presented to the hook L'', which permits the hook to be drawn downwardly to any desired extent.

The advantage of said adjustable feature is 85 that the hood may be lowered sufficiently to insure the removal of all of the smoke and vapors when the operative is not actually working over the stove, while at other times it may be more or less elevated, as desired, or 90 raised entirely out of the way. A damper, O, Fig. 1, is preferably inserted in the pipe, to be closed when the hood is not required.

It is evident that if the hood be perfectly balanced by means of the counterpoise-weight, 95 the rod M may be dispensed with; but I prefer to use the latter, as it insures more satisfactory results. Said rod may be used without the counterpoise, if desired. It is also apparent that the ventilating-pipe may be 100 connected directly with a chimney-flue or other ventilating-opening.

Having thus described my invention, what I claim, and desire to secure by Letters Patent, is—

The combination, with a cooking-stove and pipe, of a hood, a series of telescoping pipes connecting with said hood, intermediate pipe, C, and means, as the bracket J, for supporting the same in a horizontal position, a cord and pulley attached to said bracket for bal-

ancing said hood, guide-bracket H², and to notched adjusting-rod M, provided with means, as the hook L², for securing the same within said notches, all arranged and constructed as and for the purposes specified.

GOTFRID CARLSON.
